(57) **CLAIM**

I claim the ornamental design for nesting pillow, as shown and described.

DESCRIPTION

FIG. 1 is an exploded view of the nesting pillow, showing the front and two (2) sides of my new design in full lines; The FIG. 2 description is a front, side perspective view thereof; in an alternate position of use;

FIG. 3 is a front or back view thereof; and,

FIG. 4 is a side view thereof; with all four sides being the same.
